UNITED STATES PATENT OFFICE.

CHARLES IRVING FULLER, OF MCLEAN, NEW YORK.

DESIGN FOR A RUBBER FOR WASHING-MACHINES.

SPECIFICATION forming part of Design No. 30,679, dated May 2, 1899.

Application filed April 10, 1899. Serial No. 712,542. Term of patent 7 years.

To all whom it may concern:

Be it known that I, CHARLES IRVING FULLER, a citizen of the United States, residing at McLean, in the county of Tompkins and State of New York, have invented and produced a new and original Design for a Rubber for Washing-Machines, of which the following is a specification.

This invention relates to a new and original design for a rubber for washing-machines; and it has for its object to provide a design of this character that shall be both useful and ornamental.

The leading feature of the design resides in a circular body having a circular center piece, a flat circular band or rim concentric with said center piece, a circular series of cylindrical rollers grouped around the center piece and extending therefrom in radial lines to the band or rim, and a circular series of triangular blocks alternating with said rollers.

The minor features of the design are the body, having a circular base provided with the circular center piece, and a cylindrical upstanding post, arising from said center piece. An additional minor feature of the design is the rollers being provided with longitudinal corrugations.

In the drawings, Figure 1 is a perspective view of a rubber for washing-machines embodying the herein-described design. Fig. 2 is a plan view. Fig. 3 is a cross-sectional view on the line 3 3 of Fig. 2.

Referring to the accompanying drawings, the numeral 1 designates the circular body of the rubber, having a circular base-block 2, provided upon the upper side thereof with a circular center piece 3 and also with a cylindrical upstanding post 4, arising centrally from the said center piece 3. The body 1 is further provided with a flat circular band 5 of a materially-greater diameter than the centerpiece 3 and arranged concentric therewith, and a circular series of cylindrical longitudinally-corrugated rollers 6 are grouped around the center piece 3. All of the rollers 6 are of a uniform length and diameter and extend from the center piece 3 in radial lines to the band or rim 5.

The rollers 6 are spaced at regular distances apart, and alternating therewith are a series of triangular blocks 7, fitting in the spaces therebetween, said blocks having their wide ends or bases adjoining and fitting the inner side of the circular band or rim and their apices directly adjoining the center piece 3.

What is claimed is—

The design for a rubber for washing-machines, herein shown and described.

In testimony that I claim the foregoing as my own I have hereto affixed my signature in the presence of two witnesses.

CHARLES IRVING FULLER.
